John Hess } Inventor

United States Patent Office.

JOHN I. HESS, OF PHILADELPHIA, PENNSYLVANIA.

Design No. 3,598, dated August 3, 1869.

DESIGN FOR A COOK-RANGE.

The Schedule referred to in these Letters Patent and making part of the same.

To all whom it may concern:

Be it known that I, JOHN I. HESS, of the city of Philadelphia, county of Philadelphia, and State of Pennsylvania, have originated and designed a "Cooking-Range," of which the following is a full, clear, and exact description, reference being had to the accompanying engraving, making part of this specification, in which is shown a perspective view of the range, and the position of its different parts, and the ornamentations, figures, and letters formed thereon.

The ovens, three in number, are placed one above the other, and on the side of the fire-place.

The damper-plate is placed in the brick-work above the upper oven.

Above the fire-place, and between the upper oven and side-wall, is placed a shelf, provided with openings.

The ovens and fire-place doors have formed on them medallions, with radiating lines.

The medallions are enclosed by borders, the lines of which start from the corners of the doors.

The cover enclosing the opening in which is placed the ash-pan, is provided, in its centre, with a register, *z*, on each side of which are ornamentations or scroll-work.

Over the fire-place and between the second and third ovens are placed the words, "our own."

What I claim as my invention, and desire to secure by Letters Patent, is—

The design for cooking-range herein set forth.

JNO. I. HESS.
